UNITED STATES PATENT OFFICE.

EDRO RICHARDSON, OF BALTIMORE, MARYLAND, ASSIGNOR OF ONE-HALF TO THOMAS R. JENKINS, JR., OF BALTIMORE, MARYLAND.

FLUSHING-VALVE.

1,134,488.

Specification of Letters Patent.

Patented Apr. 6, 1915.

Application filed July 22, 1912. Serial No. 710,898.

To all whom it may concern:

Be it known that I, EDRO RICHARDSON, a citizen of the United States, residing at Baltimore, in the State of Maryland, have invented certain new and useful Improvements 5 in Flushing-Valves, of which the following is a specification.

This invention relates to improvements in flushing valves for any purpose where it is 10 desired to provide a flow of water for a period of time which will then automatically shut off.

The invention is particularly adapted for use in flushing water closets but may be 15 readily used elsewhere and for other purposes.

One object of the invention is to provide 20 an improved construction of the so-called push button form of flushing valve in which the flushing operation is started by simply actuating a push-button.

Another object of the invention is to materially simplify and cheapen the construction 25 of push-button flushing valves, as well as to reduce their cost of maintenance to a minimum.

With these and other objects in view the invention is illustrated in the accompanying drawing, wherein,

30 Figure 1, shows an exterior side elevation of the improved valve. Fig. 2, illustrates a vertical longitudinal section thereof on a larger scale. Fig. 3, shows a sectional plan view through the interior mechanism,—the 35 section being taken on the horizontal line 3—3 of Fig. 2. Fig. 4, illustrates another sectional plan view through the inner cylinder,—this section being taken on the horizontal line 4—4 of Fig. 2, and Fig. 5, shows 40 a horizontal section through the outer shell or casing and also through the piston stem that carries the inlet control valve,—this section being taken on the horizontal line 5—5 of Fig. 2.

45 Referring to the drawing by numerals, 1, designates a cylindrical shell or casing having an up-turned inlet nozzle, 2, that enters the shell or casing at the side and curves upwardly therefrom and whose upper end is 50 provided with an annular valve seat, 3, which has a central and horizontal position in the interior of the shell or casing. Below the inlet nozzle, the shell or casing is provided with an outlet, 4, to which the flush

pipe of a closet system is attached in any 55 suitable way.

The upper end of the shell or casing, 1, is provided with a circular cap, 5, which is attached thereto by means of screw-threads, 6, and a gasket, 7, serves to effect a sufficiently 60 tight closure between the cap and shell. The cap, 5, has a central annular recess, 8, with a shoulder, 9, at the upper end thereof which produces an enlarged central chamber, 10, at the upper end. A cylindrical sleeve, 11, 65 extends vertically in the cap from a depending circular base, 12, and said base and sleeve form a sustaining means for a vertical stem, 13. A suitable collar, 14, is interposed between the stem, 13, and the upper 70 end of the sleeve, 11, and serves as a packing about the stem. The upper end of the stem, 13, is provided with a head which forms a push-button, 15, and said head seats in the enlarged central chamber, 10, at the top of 75 the cap, 5. A spiral spring, 16, encircles the sleeve, 11, and has position in the central annular recess, 8, in which it is compressed so that its upper end will press beneath the head or button, 15, and keep the 80 same together with the stem, 13, which is carried by it, in a normally elevated position. The under side of the head or button, 15, and the upper end of the stem, 13, are detachably connected by one part having a 85 threaded plug, 17, and the other a threaded socket, 18.

The base, 12, which depends from the center of the cap pendants sustains a cylinder, 19. This cylinder has no movement in 90 the outer shell or case, 1, but is held rigidly and in a fixed position between the cap and the up-turned end of the inlet nozzle, 2. The lower pendant end of the cylinder, 19, has a head, 20, which is secured thereto by 95 means of a screw threaded flange, 21, and this cylinder head is provided with a central opening through which a piston stem, 22, passes. The upper end of the cylinder, 19, has a reduced tubular extension, 23, 100 which screws onto the base, 12, at the center of the cap, 5, and by which the cylinder is pendants sustained from the under side of said cap. This reduced extension, 23, has lateral ports, 24, through its side wall and 105 a vertical port, 25, extends down through the top wall, 26, of the cylinder so that the stem, 13, may pass through the extension, 23, and

also through the port, 25,—the latter being provided with a valve seat, 27, at its lower side so that a valve, 28, on the lower end of the stem, 13, may seat up against seat, 27, 5 and close said port. It will be noted that valve, 28, and stem, 13, are drawn upwardly by a constant spring pressure from spring, 16, and consequently the valve is always seated except in the act of setting the device 10 in operation, at which moment the push-button or head, 15, will be pushed inwardly momentarily to cause the valve to unseat but it immediately reseats when pressure on the bottom is relieved.

15 The piston stem, 22, has a reduced and exteriorly-threaded upper end, 29, and a metal washer, 30, is seated at the base of the reduced end and forms a bottom support for a flexible cup, 31, whose flanged rim, 32, 20 closely engages the inner circular wall of the cylinder and forms a piston head therein. A reinforce plate, 33, is seated on the upper side of the cup and is rigidly held thereon by means of a head, 34, that screws onto the 25 reduced end, 29, of the stem. This head is provided with a tripod-shaped guide whose arms, 35 extend upwardly and laterally therefrom and the extreme ends of said arms bear against the interior vertical wall 30 of the cylinder and serve as a guide to direct the stem, 22, in its vertical movement.

The stem, 22, has a vertical passage, 36, extending from the lower end upwardly and an adjusting screw, 37, is provided near the 35 upper end of the passage to more or less close the same. In the present instance the stem has a lateral port, 38, and the screw, 37, is arranged to more or less close the same, for a purpose presently to be described. 40 The stem has a reduced lower end, 39, and a metal washer, 40, is placed on said end to serve as a stiff backing for the upper side of a sealing disk, 41, which is also on said reduced end. Beneath the sealing disk, 41, the 45 stem is provided with a reinforce washer, 42, and a nut, 43, on the lower end securely fastens said washers and sealing disk in place on said lower end of the stem. The 50 operation of the valve is simple and as follows,—Supposing the valve to be connected with the water supply and discharge pipes and the conditions to be as shown in the sectional view in Fig. 2 of the drawing. In this normal shut-off condition, it will be 55 seen that the cylinder, 19, above the cup or piston, 31, is filled with water and that the valve or packing disk, 41, is seated on the seat, 3, of the inlet nozzle so as to cut-off the flow of water therefrom. The passage, 36, 60 through the stem, 22, establishes communication between the supply nozzle, 2, and the

upper side of the cup or piston in the cylinder, 19, and thereby provides the same pressure in said cylinder above the piston or cup as is applied to the under side of valve or 65 disk, 41. The greater area however of cup or piston, 31, insures its holding the disk, 41, seated. When it is desired to flush,—the depression of the push button or head, 15, will push valve, 28, downwardly from seat, 27 and the water in the cylinder, 19, will immediately vent through port, 25, and by lateral passages, 24, to the exterior of the 70 said cylinder. This venting of the cylinder, 19, above piston or cup, 31, will obviously 75 reduce the pressure at that side, consequently the pressure against disks, 41, and, 42, at the lower end of the piston stem will be greater than that in the cylinder after the latter is vented and disk, 41, will uncover seat, 3, on the end of inlet nozzle, 2, so that water may pass from said nozzle into the shell or casing, 1, and will flow from the latter through outlet, 4, to the closet or other point of discharge. During the flush- 80 ing operation the water from nozzle, 2, will be directed against the lower end of the passage, 36, in the stem and some of it will pass up through said passage into the cylinder, 19, and thereby gradually recharge that cylinder. 85 The time consumed in effecting this recharging of the cylinder depends upon the size of the escape port, 38, and may be varied by simply adjusting the screw, 37. As soon as the pressure in the chamber 90 19 is restored, the piston or cup, 31, therein will move downwardly and thereby seat the disk, 41, on the seat, 3, of nozzle, 2, and again cut off the flow of water.

Having thus described my invention what 100 I claim and desire to secure by Letters Patent is,—

In a flushing valve the combination with a shell having an outlet in its lower end and an upturned water-inlet above said outlet, 105 of a detachable cap at the upper end of the shell, said cap having a central depending base; a cylinder sustained by the depending base of the cap; a piston in said cylinder and having a stem whose upper end is reduced in size; and a tripod-shaped head on the reduced end of the stem and having its arms in sliding contact with the interior wall of the cylinder when the piston is making its movement. 110

115 In testimony whereof I affix my signature in presence of two witnesses.

EDRO RICHARDSON.
